UNITED STATES PATENT OFFICE.

CHARLES E. MARTIN, OF LOUISVILLE, KENTUCKY.

HAIR-DRIER.

1,364,777.

Specification of Letters Patent.

Patented Jan. 4, 1921.

Application filed June 20, 1919. Serial No. 305,485.

To all whom it may concern:

Be it known that I, CHARLES E. MARTIN, a citizen of the United States, residing at Louisville, in the county of Jefferson and 5 State of Kentucky, have invented new and useful Hair-Driers, of which the following is a specification.

This invention has reference to hair driers, and its object is to provide a drier for use 10 at swimming pools, and other places, whereby several persons may have the hair artificially dried at the same time.

In accordance with the invention, there is provided a casing or drum preferably elevated a short distance by legs, and near the upper end having an interior partition dividing the casing into an upper and relatively shallow chamber and a lower larger chamber. An elbow or duct connects the 20 two chambers and is designed to house air-driving means such as an electric fan. The lower compartment houses air heating means. Extending from the upper compartment there is a plurality of air directing means, which may be in the form of 25 funnels suitably arranged as to height and disposition to accommodate several people at the same time.

The invention will be best understood 30 from a consideration of the following detailed description taken in connection with the accompanying drawings forming part of this specification, with the understanding, however, that the invention is not confined to any strict conformity with the showing of the drawings, but may be changed and modified so long as such changes and modifications mark no material departure from the salient features of the invention as 35 expressed in the appended claims.

In the drawings:—

Figure 1 is a perspective view of the hair drying apparatus.

Fig. 2 is a diametric vertical section 45 thereof.

Fig. 3 is a section on the line 3—3 of Fig. 2.

Fig. 4 is a section on the line 4—4 of Fig. 2.

50 Referring to the drawings there is shown a drum 1 which may be of cylindrical shape, as shown in the drawings, or of any other appropriate shape. The drum is shown as mounted upon legs 2 thereby elevating it 55 a short distance but it is to be understood that the drum may be supported in other

ways than upon legs. The interior of the drum is divided into two compartments 3, 4 respectively, by a partition 5 which may be considered as extending horizontally 60 across the interior of the drum. The partition 5 is located nearer to the top of the drum than to the bottom thereof, whereby the chamber 3 is considerably smaller in capacity than the chamber 4, considering the 65 drum as of even diameter throughout. It is to be understood that the invention is not confined to any particular drum or body member 1, or any particular position of the partition 5.

70 In the bottom of the drum there is located a section 6 which may be made of woven wire fabric, the section 6 providing communication between the interior of the bottom portion of the chamber 4 and the atmosphere. Lodged above the wire fabric section 6 is a heater 7 which may be of any of the familiar forms of gas heaters, such as a hot plate, and this heater is fed with fuel by a pipe 8 extending to some exterior source 80 of gas.

Within the chamber 4 is an elbow 9 opening at one end 10 through the partition 5, and at the other end opening into the chamber 4 and carrying an electric fan 11 or any 85 other suitable type of air propelling device driven by a motor 11^a fed with current through a conductor 12 including a suitable form of electric switch 13, the conductor being assumed to be connected to a source 90 of current such as a service line. By placing the motor 11^a outside of the chamber 4 there is no danger of overheating and so injuring the motor or conductors. Adjacent to the heater 7 the drum 1 is provided 95 with a door 14 and in position to give access to the electric fan 11 there is another door 15 in the walls of the drum 1. In order to strengthen the elbow 9 suitable braces 16 are provided. At any convenient point in 100 the drum 1, preferably at a high point in the chamber 4 there is an outlet flue 17 for gases of combustion.

105 The walls of the chamber 3 are provided with numerous openings 18 each covered by a guide 19 for a slide or damper 20 and alining with each hole 18 is a funnel 21 with the large end outward. The funnels 21 may be all arranged at the same height, say about four feet from the floor, although such particular height is not obligatory. The height mentioned, however, will accommodate 110

grown people seated upon chairs or stools and children standing upright, the funnels 21 being then about on a level with the heads of the persons.

5 When it is desired to use the drier, the heater 7 is lighted, thus heating the air in the chamber 4. The heat may be regulated by a valve 22 at the heater 7 and accessible through the door 14, or in any other suitable manner. When the air within the drum 1 is sufficiently heated the motor 11 is started and the heated air from the chamber 4 is forced through the elbow 9 upwardly into the chamber 3 at about the 10 mid-point thereof. The heated air distributes through the chamber 3 and out through the openings 18 or such of these openings as are not closed or partially closed by the dampers 20. The heated air 15 is projected in expanding streams through and from the funnels 21 and the hair of the persons being treated is subjected to the hot air, thereby quickly drying the hair and at the same time thoroughly aerating it. The 20 amount and force of the air streams may be readily regulated at each funnel 21 by the slide 20. The degree of heat imparted to the air in the chamber 4 may be readily regulated by the valve 22. The force of 25 the air streams issuing from the funnels 21 may be further regulated by the control of the electric fan 11. The flue 17 permits the escape of the gases of combustion from the heater 7 when the fan 11 is not in operation.

30 It will be understood that where other sources of heat than gas are available other types of heaters than the gas heater 7 may be used. Where steam heat is available, steam coils may be installed inside of the 35 drum 4 and in some instances it may be economical to employ electric heaters. These, however, are matters of convenience 40 and environment.

The hair drier is particularly valuable in 45 places such as club houses, bathing resorts, swimming pools and the like, where numerous persons desire the hair to be dried, and the multiple hair drier of the invention makes it feasible to so treat a number of 50 persons simultaneously with the instrumentalities employed, with such instrumentalities of small compass.

What is claimed is:—

1. A multiple hair drier comprising a 55 drum internally divided into upper and lower chambers with communication between them, the upper chamber having a series of air directing devices extending therefrom, the lower chamber having heating means therein and the sole means of 60 communication between the chambers having air propelling means, whereby air heated in the lower chamber may be driven into the upper chamber and distributed through 65 the various air directing devices.

2. A multiple hair drier comprising a drum with a partition within it dividing the drum into upper and lower chambers, an elbow duct in the lower chamber extending through the partition and constituting a 70 means of communication between the two chambers, air heating means within the lower chamber, air propelling means in the elbow, and a series of air directing devices arranged about and extending from the 75 upper chamber, whereby air may be heated in the lower chamber, propelled through the elbow into the upper chamber and escape through the air directing devices from the 80 upper chamber.

3. A multiple hair drier comprising a drum with a partition within it dividing the drum into upper and lower chambers, an elbow duct in the lower chamber extending through the partition and constituting a 85 means of communication between the two chambers, air heating means within the lower chamber, air propelling means in the elbow, and a series of air directing devices arranged about and extending from the 90 upper chamber, whereby air may be heated in the lower chamber, propelled through the elbow into the upper chamber and escape through the air directing devices from the 95 upper chamber, each air directing device having controlling means for determining the amount of air escaping therefrom.

4. A hair drying apparatus comprising a casing with an interior partition dividing the casing into upper and lower compartments, a duct between the two compartments entering the upper compartment in an upward direction, heating means in the lower compartment, power driven air-propelling means in the duct for causing the 100 forceful flow of air from the lower compartment to the upper compartment, and means for directing heated air laterally 105 from the upper compartment.

5. A multiple hair drier comprising an 110 upright drum with a partition therein dividing the interior of the drum into upper and lower compartments, heating means for air in the lower compartment, a duct in the lower compartment opening upwardly 115 through the partition, air propelling means in the duct, and air directing devices communicating with the upper compartment about the periphery thereof and projecting therefrom in different directions, the air directing devices being all arranged at substantially the same height, and controlling means for each air directing device movable to determine the amount and force of air issuing therefrom.

6. A multiple hair drier comprising an 120 upright drum with an interior partition dividing the drum into upper and lower compartments, with the lower compartment 125 larger than the upper compartment, an el-

- bow duct in the lower compartment opening upwardly through the partition into the upper compartment, heating means in the lower compartment with an air inlet in the 5 said lower compartment associated with the heating means, an electric fan in the lower compartment at the entrance of the elbow duct to propel air into the upper compartment, doors in the lower compartment for 10 giving access to the heating means and the fan, a flue in the lower compartment for the escape of gases of combustion, and a series of funnels arranged about the upper compartment and projecting horizontally therefrom for directing the heated air in different directions from said upper compartment. 15
7. A multiple hair drier comprising an upright drum with an interior partition dividing the drum into upper and lower compartments, with the lower compartment larger than the upper compartment, an elbow duct in the lower compartment opening upwardly through the partition into the upper compartment, heating means in the 20 lower compartment with an air inlet in the said lower compartment associated with the heating means, an electric fan in the lower compartment at the entrance of the elbow 25
- duct to propel air into the upper compartment, doors in the lower compartment for giving access to the heating means and the fan, a flue in the lower compartment for the escape of gases of combustion, and a series of funnels arranged about the upper compartment and projecting horizontally therefrom for directing the heated air in different directions from said upper compartment. 30
8. A hair drier comprising a casing with upper and lower communicating compartments, the upper compartment being shallower than the lower compartment, means in the lower compartment for driving air therefrom into the upper compartment, and means for directing air from the upper compartment laterally therefrom in various directions. 35
- In testimony that I claim the foregoing as my own, I have hereto affixed my signature. 40
